CLAIM

The ornamental design for a remote control, as shown and described.

DESCRIPTION

FIG. 1 is a front elevation of a remote control of the present invention;

FIG. 2 is a left side elevation;

FIG. 3 is a rear elevation;

FIG. 4 is a bottom plan;

FIG. 5 is a top plan;

FIG. 6 is a front perspective; and,

FIG. 7 is a rear perspective.

The broken line characters on the buttons in the figures form no part of the claimed design.
